WASHER BOX FOR COAL AND THE LIKE

Bertram Norton, Claverley, England, assignor to
The McNally-Pittsburg Mfg. Corp., Pittsburg,
Kans., a corporation of Kansas

Application March 14, 1934, Serial No. 715,553
In Great Britain October 18, 1933

9 Claims. (Cl. 209—496)

This invention relates to washer boxes for coal and the like of the type in which separation of the refuse, which constitutes the specifically heavier material, from the remainder, which 5 is generally coal and constitutes the specifically lighter material, is effected by causing water to rise and fall in pulsations through perforated plating on which the material to be washed rests. The invention is concerned with washer 10 boxes of this type in which the rate of discharge of the refuse or shale is controlled automatically in accordance with the depth of the refuse bed. As a rule such automatic control is effected through the medium of a float which 15 sinks through the coal that rests upon the refuse, and which is connected through a relay mechanism to means by which the flow of refuse through a discharge opening in the washing compartment proper is arrested or retarded.

20 In my prior Patent 1,806,493, issued May 19, 1931, I have described and claimed an arresting mechanism in the form of an adjustable barrier or weir which co-operates with a shelf projecting outwards from the lower edge of the 25 discharge opening for the refuse. The use of such a weir in combination with a float leads to excellent separation of the coal from the shale or other refuse, but I have found that in practice some coal still tends to pass through the 30 discharge opening with the refuse.

According to the invention, in a washer box in which there is a mechanism operative to arrest or release the flow of refuse through a discharge opening in accordance with the depth 35 of the refuse bed, separate means are provided for retarding the flow of refuse outside the discharge opening when such flow starts. At the start of this flow I have found that a reduction in density or pressure is produced in the refuse 40 bed in the washing compartment proper, and that this reduction affects the accurate operation of any float that is employed for controlling the operation of the washer box. Moreover, the reduction in pressure also results in some of the 45 coal that is immediately above the refuse bed being drawn downwards and passing outwards with the refuse. This is prevented completely, or to a very large extent, if the flow of the refuse is retarded in accordance with the invention.

50 In the preferred construction I use a shelf projecting outwards from the bottom of the discharge opening and provide means for retarding the flow of the refuse across this shelf. It is to be understood that such means are entirely 55 separate from any means used for ar-

resting or releasing the flow and are designed to act as a brake when the flow has begun. Preferably a hinged flap is provided above the shelf to press downwards on the outgoing refuse moving across the shelf.

In order that the invention may be clearly understood and readily carried into effect, one washer box constructed in accordance therewith will now be described by way of example with reference to the accompanying drawings, in 10 which

Fig. 1 is a top plan view of a portion of the washer box embodying the invention;

Fig. 2 is a sectional view taken along the line 2—2 of Fig. 1;

Fig. 3 is a sectional view taken along the line 3—3 of Fig. 2;

Fig. 4 is an enlarged sectional view taken along the line 4—4 of Fig. 3;

Fig. 5 is a sectional view taken along the line 5—5 of Fig. 4; and

Figs. 6, 7, and 8 are diagrammatic views illustrating the movement of shale from the washer box.

The coal to be washed is fed into the box 10 through an inlet chute 11 and passes onto a perforated bed 12 on which it is agitated by water pulsating through the bed. The coal and refuse separate into layers, the coal passing out of the box by an outlet at the opposite end and the refuse passing through an aperture 13, the depth of which is controlled by an adjustable plate 14. A shelf 15 extends outwards from the base of this aperture and an adjustable barrier or weir 16, in the form of a sector of a cylinder pivotally mounted to rock about an axis 17, co-operates with the end of the shelf. In the full line position shown in Figs. 2 and 4, the weir effectively prevents the outflow of refuse through the aperture 13.

When, however, the weir is moved into the dotted line position shown in Fig. 4, the refuse can flow through the aperture 13, across the shelf 15, and over the edge of the weir. It then drops into a refuse compartment 23, from which it is removed by elevators, not shown. The weir is operated through a relay mechanism comprising cylinders 18 and 19 arranged to move the lever 20. The relay mechanism is controlled through the medium of a float 21 through the medium of a parallel motion linkage 22. The construction described so far is identical in principle with that described in my prior Patent 1,806,493.

In order to control the rate of discharge of 55

the refuse 24 over the shelf 15 and to reduce to a minimum the risk of coal passing to the refuse compartment with the refuse, a flap 25, hinged at 26 to a plate 27, is provided to rest 5 on the outflowing refuse. The outer edge of this flap is connected to a rod 28, which is hinged at its upper end to a lever 29 pivoted at 30 and carrying an adjustable balance weight 31. By adjustment of the weight 31 the pressure exerted by the flap 25 on the outgoing refuse can 10 be regulated. The rod 28 passes upwards through a tube 32 in the coal inlet chute 11. A bracket 33 on which the lever 29 is pivoted at 30 is fixed to the tube 32. The rod is provided 15 with an adjustable collar 34 having threaded relation with the rod 28, and when this comes into contact with the bracket 33 the rod 28 cannot move downwards any further. The upward movement of the rod 28 is limited by an adjustable stop 35 carried by the bracket 33 and placed in the path of the lever 29.

In order to illustrate the effect produced by means of the novel mechanism the formation assumed by the refuse in various circumstances 25 is illustrated diagrammatically in Figs. 6, 7, and 8.

Fig. 6 shows the adjustable weir 16 in its highest position. The refuse has built up on the shelf 15, and in so doing has increased the density at the point 36. When the pivoted weir is moved 30 downwards under the control of the float 21 contacting with the bed 24, some of the refuse on the shelf is immediately discharged, with the result that the pressure in the adjacent part of the refuse bed is reduced. The position immediately after the lowering of the weir 16 is 35 illustrated in Fig. 7. Without the flap 25 a depression or hollow 37 tends to form in the refuse bed 24 beneath the float 21, as illustrated in Fig. 8, because the endwise movement of the refuse bed is slower than that of the refuse on the shelf 15. My flap 25 acts as a brake on the flow of the refuse passing over the shelf 15 in such a manner as to prevent the formation of such a depression, thus providing a refuse bed of 40 uniform depth, whereby accurate operation of the float is attained and a material reduction in the coal lost with the shale.

Without further elaboration the foregoing will so fully explain my invention that others may, 50 by applying current knowledge, readily adapt the same for use under various conditions of service.

I claim:

1. A device of the type described comprising a washer box having a gate controlled outlet opening 55 for refuse separated from the coal, a float controlled mechanism for opening and closing the gate, a refuse retarding plate pivotally connected with the box and arranged to press downwardly on the refuse passing through said opening, means for varying the effective pressure of said plate, said means being independent of said float controlled mechanism.

2. A device of the type described comprising a washer box for coal having an outlet opening 65 for refuse separated from the coal, a shelf carried by the washer box and arranged to carry the refuse passing through said opening, a movable gate positioned at the discharge edge of said shelf for controlling the movement of refuse 70 delivered to the shelf, a float controlled mechanism for operating the gate, the float being actuated by the bed of refuse separated from the coal, a flap hingedly connected with the box and extending over the shelf in spaced relation therewith, said flap being arranged to press down-

wardly on the refuse passing over the shelf, to retard the movement of the same, and means for varying the pressure of the flap upon the refuse, said flap and said means being independent of said float controlled mechanism.

3. In a jig washer, the combination of a washing chamber formed with a refuse discharge opening, a shelf positioned outside the discharge opening for receiving refuse passing therethrough, a flap adjustably and hingedly connected with the washer above said discharge opening and arranged to press downwardly on the refuse passing across the shelf, a weighted balance lever, and an operating connection between the weighted balance lever and the free side of the flap.

4. In a jig washer, the combination of a washing chamber formed with a refuse discharge opening, a shelf disposed outside said discharge opening to receive refuse passing therethrough, means for arresting or releasing the flow of refuse through said discharge opening and from said shelf, and a flap mounted above said shelf and adapted to press downwards on outgoing refuse.

5. In a jig washer, the combination of a washing chamber formed with a refuse discharge opening, a shelf disposed outside said discharge opening to receive refuse passing therethrough, means for arresting or releasing the flow of refuse through said discharge opening and from said shelf, a flap in hinged connection with the washer, 30 said flap being mounted above said shelf and being adapted to press downwards on refuse on said shelf, and means for controlling the downward pressure exerted by said flap.

6. In a jig washer, the combination claimed 35 in claim 5, wherein said controlling means comprise a weighted balance lever and means connecting said lever to the outer or free end of said flap.

7. In a jig washer, the combination of a washing chamber provided with a refuse discharge opening, a shelf to receive refuse from the opening for passage thereover, means for arresting or releasing the flow of refuse through the opening 45 and from the shelf, and means to yieldably press upon the refuse as it passes over the shelf for controlling the flow thereof through the opening so as to maintain a refuse bed of uniform depth within the chamber.

8. In a jig washer, the combination of a washing chamber provided with a refuse discharge opening, supporting means to receive the refuse from the opening for passage thereover, mechanism including float means within the chamber and means exteriorly thereof to arrest or release 55 the flow of refuse through the opening and from the shelf in accordance with the depth of the refuse bed in said chamber, and yielding means to bear upon the refuse as it passes over the supporting means for controlling the flow thereof 60 through the opening so as to maintain a refuse bed of uniform depth within the chamber.

9. In a jig washer, the combination of a washing chamber provided with a refuse discharge opening, a shelf to receive the refuse from the opening for passage thereover, float actuated means for arresting or releasing the flow of refuse through the opening and from the shelf in accordance with the depth of the refuse bed in the chamber, and means to yieldably bear 70 upon the refuse as it passes over the shelf for controlling the flow thereof through the opening so as to maintain a refuse bed of uniform depth within the chamber.
